SHEET-METAL WORKER'S HAMMER

Anthony V. Crement, Chicago, Ill.

Application October 7, 1957, Serial No. 688,640

3 Claims. (Cl. 81—15)

This invention relates in general to tools and in particular to a sheet metal worker's hammer.

In sheet metal work, particularly in the forming of ducts and similar structures where Pittsburgh joints are used, it is highly desirable to facilitate the completion of the Pittsburgh joints as it is a time consuming process since the joints must be well seated and the flanges completely and neatly bent over and locked throughout their entire length.

Various tools have been devised for this purpose but insofar as I am aware none of the tools in the prior art have the features of the tool described and claimed hereinafter.

In the completion of a Pittsburgh joint the first operation is to seat one flange well into a joint and the second operation is to bend the locking flange completely over in a neat manner throughout its entire length.

Although flat-sided hammers are known and can be used for certain of these operations, insofar as I am aware no hammer has been devised in which the handle has a special curve or configuration and is so related to the hammer head as to present one relation between the hammer head and the work when held in one position, and another relation between the hammer head and the work when held in another position. These relationships are important for ease and rapidity in the locking of the Pittsburgh joint as will be seen from the following.

The primary object of the invention, therefore, is to provide a sheetmetal worker's hammer with a head having substantially parallel faces and a handle having an angular shank where it attaches to the hammer head, whereby the hand grip portion of the handle will be angularly related to the working faces of the hammer head.

It is another object of my invention to provide a sheetmetal worker's hammer in which the relationship of the hammer head to the handle is such that the worker's hand gripping the hammer handle cannot come in contact with the work regardless of the operation being performed in the locking of a Pittsburgh joint.

And one more object of my invention is to form the hammer head and handle of metal in one piece to give strength and permanency to the tool.

Other objects and advantages as well as the construction and manner of use of my invention will be apparent by reference to the following specification in connection with the accompanying drawing in which:

Fig. 1 is a side elevational view of my hammer when used in one position.

Fig. 2 is a similar view of the hammer turned 180° when used in another position.

Fig. 3 is a fragmentary elevational view of the long face of the hammer.

Fig. 4 is an end view of the hammer head with its curved edges.

Fig. 5 is a fragmentary end view through a Pittsburgh joint with the hammer being used in one position to assemble the joint.

2

Fig. 6 is a similar view with the hammer being used in another position to make the first bend of the locking flange.

Fig. 7 is a fragmentary isometric view of the joint and hammer again reversed and used to make the final bend of the locking flange.

Referring now to the drawing by numerals of reference, 1 designates a hammer handle with an angular shank 2 adjacent the hammer head 3. The hammer head 10 may be substantially square in cross section and elongated as shown in Figs. 3 and 4. It is important that the sides 4—4' of the hammer head be substantially parallel to angular shank 2 of the handle and angularly related to the handle 1. Edges 5 are curved as shown to prevent sharp denting of the metal when using the hammer. It is preferred that the handle and the hammer head be formed of metal in one piece, although a separate handle may be used and suitably joined to the hammer head.

As will be seen in Fig. 5, when the hammer is used 20 to drive flange 6 of sheet metal side 7 home into the reverse bend 8 on side 9, the side 4 of said hammer is parallel to and adjacent side 7 and the handle 1, angling as it does away from the hammer head keeps the operator's hand well clear of the work and prevents denting 25 of the sheet metal. If the handle was not curved as shown but was of conventional construction, the tendency would be to angle the hammer head to keep from hitting one's hand and this would most likely cause denting of the sheet metal, because the hammer head would 30 not be parallel to the side 7.

After the flange 6 is well seated in the reverse bend 8 the next step is to bend locking flange 10 through an angle of 90° and into contact with side 7.

The best practice is to do this in two stages making 35 the first bend at least 45° or more. This is done by reversing the hammer 180° so that side 4' is closest to the work with shank 2 of the handle angling away from the work and the handle 1 parallel to but well spaced from side 7, so the operator's hand will be clear at the end of 40 each stroke.

With the side 4' of the hammer head at an angle to the locking flange 10 each stroke of the hammer will bend each portion of said flange at approximately the same angle as the hammer travels along the flange as shown 45 by dotted lines in Fig. 6.

In the next and final stage the hammer is again reversed 50 180° to place face 4 of the hammer head adjacent locking flange 10 and substantially parallel to the side 7 with the handle 1 angling away from the work. Now the operator again travels the length of the locking flange and drives it home against side 7 in a neat, efficient and expeditious manner, with no danger of 55 hitting his fingers on the work and making a uniform appearing bend with little or no wrinkles, creases or dents.

From the foregoing it will be seen that I have provided 60 a new and simple arrangement in a sheetmetal worker's hammer which will make it possible for him to perform the function of assembling and locking a Pittsburgh joint in a more expeditious and neater manner than was heretofore possible with present day tools.

Obviously, slight changes in form, proportion and details of construction may be resorted to without departing from the spirit of my invention and I reserve all rights to such changes as come within the scope of this 65 specification and the claims which follow.

What I claim as new and desire to secure by Letters Patent is:

1. A sheetmetal worker's hammer comprising a handle, an elongated hammer head having its long dimension 70 transversely disposed in relation to the handle, a shank on the handle adjacent the hammer head and in alignment with two oppositely disposed elongated sides of said

hammer head, the end portion of the handle being angularly disposed in one plane to the shank on said handle and to the oppositely disposed elongated sides of said hammer.

2. The structure as specified in claim 1, the edges 5 of the hammer head at the ends of the elongated sides being curved.

3. A sheet metal worker's hammer comprising a handle, an elongated hammer head having its long dimension transversely disposed in relation to the handle, pairs 10 of oppositely disposed elongated sides on the hammer head, a shank on the handle adjacent the hammer head and in planar alignment with the two oppositely disposed elongated sides of said hammer head, the end portion of

the handle extending from the shank being angularly disposed to said shank.
